UNITED STATES PATENT OFFICE.

HILARY HENRY DADSON, OF LONDON, ENGLAND, ASSIGNOR OF ONE-HALF TO
LEONARD SMITH, OF LONDON, ENGLAND.

TOBACCO PIPE.

Application filed March 23, 1925, Serial No. 17,809, and in Great Britain November 19, 1924.

My British patent specification No. 205,361 describes a tobacco pipe comprising a tobacco retaining receptacle screwed within a secondary chamber in which is located a plain loose fitting cup without grooves or partitions forming a relatively shallow receptacle for the nicotine, the effect of such an arrangement being to cause the smoke from the bowl to be drawn into the secondary chamber below the bottom of the tobacco retaining receptacle and thereafter to rise and pass over the edge of the aforesaid loose fitting cup and thence pass to the bore in the stem of the pipe, for the purpose of preventing moisture from the mouth of the smoker passing into the tobacco holding receptacle.

The present invention consists of certain modifications of or improvements in or relating to the pipe described in my said British patent specification No. 205,361.

According to my present invention, a tobacco pipe of the kind referred to has a disc or pad or body of absorbent material (which may be flat or slightly cupped or of any suitable shape) fitting loosely within the secondary chamber, with the disc pad or body and the chamber and the bore of the stem where it enters the chamber so formed in relation to one another that the smoke passage from said chamber can not in any position become blocked by said disc pad or body.

The secondary chamber according to my present invention is preferably low and broad and has the central bottom portion formed flat or of flattened form or curved to a radius different from that of the upwardly extending surrounding wall of said secondary chamber which wall is advantageously curved, and according to a further feature of my invention the bore of the stem where it enters said chamber is enlarged to form a recess or niche in the wall of said chamber extending upwards to or nearly to the bottom of the tobacco holding portion so as always to ensure a free passage for the smoke from the secondary chamber into the bore of the stem; thus for example should the disc be moved (for instance when the parts are unscrewed) to such a position that it tends to block the opening to the stem, the tobacco holding part when screwed fully home will contact with the edge of the disc and move it away to uncover the

enlargement of the stem opening and ensure a free passage for the smoke.

The loosely fitting disc or pad or body for use in the secondary chamber according to the present invention is made of a suitable absorbent material, for example of paper as hereinafter described.

A form of construction in accordance with the present invention is illustrated in the accompanying drawings, in which:—

Fig. 1 is a side view in elevation of the pipe.

Fig. 2 shows the bowl and stem in vertical longitudinal section, and

Fig. 3 is a local sectional plan taken on the line 3—3 Fig. 2.

Referring to these drawings:—

The separable upper part of the bowl or tobacco holding receptacle A is screwed into the lower part B in which is the secondary chamber C to contain a loose fitting disc or pad or body D (shown cup-shaped in the drawings) of absorbent material; for instance compressed paper.

It is preferable, though not essential, that the transverse division of the bowl be about midway down same or even below the middle, as illustrated, since the bowl is usually thickest at that part and the screw threads may be of fair depth without fear of breakage.

The secondary chamber C is shallow and occupies but little space. A recess or niche E is provided where the bore F enters the chamber C and this recess extends upwards to the underside of the part A, so that no matter how the disc or body D is shaken about in the chamber C it cannot completely block the bore F.

The smoke passes from the tobacco holding receptacle A through a central hole G (or it may be a series of holes) and impinges directly on the disc or body D, which absorbs the nicotine as well as any moisture from the mouth of the smoker the smoke then passing (over the rim or edge of the disc or body) to the stem F.

H is the usual mouthpiece.

The disc, pad or body of absorbent material may be either round or of other suitable shape and may either be flat or other than flat for example same may be of cup or disc or saucer form; and may be of any suitable material of an absorbent character for example of paper, cardboard, carton, wood

pulp or paper pulp or equivalent moulded or otherwise formed into the desired shape.

This disc or pad or body (such as D) whatever its shape or form is of somewhat 5 less diameter if circular, or somewhat less in size, than the diameter or the interior of the said secondary chamber in which same is used.

The exterior form of the bowl (or/and 10 stem) of the pipe may be of any desired and suitable shape or pattern for example of the exterior shown in the accompanying drawing or of the well-known bull-dog pattern and either with straight or bent stem.

15 What I claim is:—

A tobacco pipe having a transversely divisible bowl the upper part forming a tobacco-holding receptacle and the lower part a relatively shallow secondary chamber adapted for receiving a pad of absorbent material of smaller dimensions than said secondary chamber, said secondary chamber having a substantially vertical niche in its wall forming the termination of the bore of the stem where it enters said secondary chamber, said niche extending from the floor of said secondary chamber past the bore and upwardly towards the underside of the tobacco-holding receptacle. 20 25

HILARY HENRY DADSON.
